TOILET SEAT COVER HINGE LEAF

Leslie H. Coggins, Cross St., Meriden, Conn.

Filed June 5, 1959, Ser. No. 56,226

Term of patent 14 years

(Cl. D4—5)

Fig. 1

Fig. 2

Fig. 3

Fig. 5

Fig. 4

Fig. 1 is a front elevational view of a toilet seat cover hinge leaf showing my new design.

Fig. 2 is a side elevational view thereof,

Fig. 3 is a bottom plan view thereof,

Fig. 4 is a top plan view thereof, and

Fig. 5 is a cross-sectional view thereof taken on line 5—5 of Fig. 1.

I claim:

The ornamental design for a toilet seat cover hinge leaf, substantially as shown.
